Attorneys

UNITED STATES PATENT OFFICE.

GEORGE EDWARD DICKS, OF LANGLEY, NEAR BIRMINGHAM, ENGLAND.

SNAP MOLDER'S FLASK.

Application filed November 25, 1922. Serial No. 602,307.

To all whom it may concern:

Be it known that I, GEORGE EDWARD DICKS, a subject of the King of Great Britain and Ireland, and resident of 11 St. 5 Johns Road, Langley, near Birmingham, England, have invented a new and useful Improvement in Snap Molders' Flasks, of which the following is a specification.

This invention relates to an improved 10 construction of snap molder's flask which is adjustable in size to suit different sizes of castings which may be required to be moulded therein.

The object of this invention is to provide 15 an improved construction of such adjustable flask which is formed in two main sections hinged together and adapted to be secured by a lever catch. The adjustability of the flask permits a greater variety of 20 work to be moulded in any particular flask, and reduces the number of sizes required for the equipment of a foundry.

My invention will now be described with 25 reference to the accompanying drawings in which:—

Figure 1 is a plan of an adjustable snap moulding flask constructed according to my invention.

Figure 2 is a side elevation of the same. 30 Figure 3 is an end view.

Figures 4 and 5 are details showing the method of securing the two portions of the flask together at one corner, and

Figures 6 and 7 are similar views showing 35 the two corners separated.

Referring to the drawings, the flask is formed of two sections 1 and 2 attached together by a hinged connection 3 at one corner, and adapted to be secured at the 40 other corner by a lever catch 4. Each of the sections 1 and 2 comprises an angle piece 5 of channel section and preferably formed slightly hollow on its inner face. These 45 portions may be of cast iron or may be pressed from sheet material or otherwise suitably constructed. They are provided with outwardly projecting flanges 6 at their upper and lower edges, and grooves 7 are 50 provided in the inner face of each of these flanges 6 as will be seen more clearly in

Figure 5. These grooves 7 form guides in which engage connecting plates 8 shaped to correspond with the channel form of the corner pieces 5. These connecting plates are of a sufficient length to project at each 55 end of the corner piece 5 and serve as connections to the two short sections 9 and 10 which form the other corners of the flask. The two short sections 9 are hinged together at 3 as already described, whilst the 60 two sections 10 are respectively provided with a hook 11 and an eye 12 to the latter of which is hinged the lever catch 4 adapted to be rotated about its eye so as to engage it over the hook 11 as shown in Figures 65 4 and 5. The connecting plates 8 are each provided with a pair of slots 13 in which engage screwed studs 14 secured in the corner pieces 5 and the sections 9 and 10 respectively. Wing nuts 15 are provided 70 on these screwed studs 14 so as to clamp the portions of the flask in any desired position.

The flask may be adjusted in size by slackening the wing nuts 15 and sliding the 75 corner pieces 5 and the sections 9 or 10 thereon so as to increase or decrease the size of the flask. When the parts are set so as to obtain the required size, the wing nuts 15 are again tightened so as to clamp 80 them in position. When the flask is in use it may be opened by swinging the catch 4 about its eye 12 so as to release it from the hook 11. The two sections of the flask may then be opened out about a diagonal 85 line pivoting upon the hinge 3 between the two sections 9. In order to ensure a good joint between the two sections 10 and maintain the parts in correct alignment when the flask is closed, one of these sections 10 is 90 provided with a recess 16 with which a corresponding projection 17 on the other section engages. This recess 16 and the projection 17 are formed with corresponding inclined upper and lower edges 18 and 19 95 to ensure easy engagement, and a correct fit. Two of the connecting plates 8 are provided with projecting bosses 20 which serve as handles and also as lugs for the reception of registering pins adapted to 100

be inserted in the holes 21 formed therein, so as to register two flasks in position, one upon the other.

I claim:—

- 5 An adjustable snap moulding flask comprising a pair of corner pieces, a pair of short sections, a hinge connection between these short sections, a second pair of short sections each having one end mitred, re-

leasable fastening means for said sections, 10 the mitred end of one of said sections having a taper sided recess, a co-operating taper sided projection upon the mitred end of the other section and adjustable connecting plates for said short sections and corner pieces. 15

GEORGE EDWARD DICKS.
